CONTINUOUS CASTING APPARATUS FOR
CASTING CORRUGATED CYLINDERS

George N. Menasoff, Tarrytown, N.Y., assignor, by mesne
assignments, to Anaconda Wire and Cable Company, a
corporation of Delaware

Filed Oct. 16, 1961, Ser. No. 145,064
3 Claims. (Cl. 22—57.2)

My invention relates to casting apparatus and particularly to apparatus for continuously casting an elongated cylindrical article of indefinite length.

It has been known to obtain continuous lengths of cylindrical articles comprising materials such as aluminum, copper, and even steel by processes of extrusion. In extrusion processes the material to be extruded is heated to a temperature below its melting point and forced through dies by the application of very great pressure. Particularly it has been known to apply cable sheaths by the methods of extrusion, such sheaths being commonly formed of lead and lead alloys and of aluminum. A serious limitation of extrusion processes, however, has resided in the cost and complexity of the apparatus due to the high pressures required. Another limitation has resided in the small size of the charges of materials, such as aluminum, that can be put into an extrusion chamber. This severely reduces the lengths of the extruded shapes that can be manufactured without discontinuities or weld marks and is a particular handicap in the case of aluminum cable sheathing which is always subjected to a certain amount of flexing.

I have overcome these limitations by an apparatus that continuously casts material in cylindrical form. Due to the fact that high pressures are not required for casting, the apparatus of my invention is much less costly than a similar apparatus for extrusion and since material is fed into my casting apparatus in a molten state it can operate continuously without interruption for charging.

My apparatus for casting an elongated article comprises a cylindrical die with an internal helical groove, means for introducing a liquid, solidifiable material into the die and means for cooling the apparatus to form the material into a cylinder with an external projection matching the groove in the die. My apparatus also comprises means for cooling and means for rotating the die so as to eject the cylinder by the interaction of the projection on the cylinder with the groove in the die. For casting a hollow cylinder my apparatus is comprised as above but with a cylindrical core.

Embodiments of my apparatus have helically grooved cores and smooth-walled dies, helically grooved dies and smooth-walled cores or helically grooved dies with matching helical threads on the cores. For continuously casting a cable sheath my apparatus has a core tube with a bore for receiving a cable. I have also provided my apparatus with means for supplying molten aluminum, a closed chamber for molten aluminum surrounding the core tube with the core tube extending above the level of molten aluminum in the chamber, means for maintaining a gas under pressure above the aluminum in the chamber, conduit means between the chamber and the storage supply, and pumping means for pumping molten aluminum through the conduit into the chamber. My apparatus also comprises means for swaging the sheath onto the cable.

A more thorough understanding of my invention will be obtained from a study of the appended drawing.

In the drawing:

FIGURE 1 is an elevational view, partly in section, of the apparatus of my invention.

FIGURE 2 is an elevational view, partly in section, of another embodiment of the apparatus of my invention.

2

FIGURE 3 is a section in elevation of a detail of still another embodiment of my invention.

Referring to FIGURE 1, a casting machine indicated generally by the numeral 10 is connected to a supply tank of molten aluminum 11 by means of a heat insulated pipe line 12 containing a valve 13. Although I have shown apparatus for casting aluminum it will be understood that I do not wish to be limited thereto and that my apparatus is suitable for continuously casting other metals and alloys such as copper and lead and is not limited to metals but can also be used for casting other materials that pass from a liquid to a solid state. The pipe 12 feeds into a funnel-shaped chamber 14 at the top of the apparatus 10 communicating with a cylindrical die 15 through an opening 16. A seal 17 preferably of a lubricated, high-temperature type of which several are known prevents the escape of molten aluminum between the chamber 14 and the die 15. The die 15 is threaded with an internal helical groove 18 which I have shown to extend the full length of the die. It will be understood, however, that the groove 18 may start at some point below the top of the die 15. Although I prefer the groove to have a single flight it will be understood that grooves of two or more flights may also be used within the scope of my invention.

Molten aluminum from the supply 11 forms a pool 19 in the chamber 14 which flows under the influence of gravity, augmented, where desired, by pressure inducing means hereinafter to be described, through the opening 16 of the conical chamber 14. The die 15 is enclosed in a jacket 21 with passages 22 for a cooling fluid 23. I prefer to use water as the cooling fluid 23 for casting aluminum but I do not wish to be limited by this preference and it will be understood that other liquid and gaseous cooling media may also be used to cool the die 15. The fluid 23 is introduced into the passages 22 through an aperture 24a from a source of such fluid, not shown, and leaves through another aperture 24b to a cooling plant or sewer not shown. The die 15 has a bottom flange 25 and a lubricated seal 26 is interposed between this flange 25 and the jacket 21. A sprocket ring 27 is locked onto the flange 25 by means of a set screw 28 and connected to a sprocket wheel 29 by means of a chain belt 30. The sprocket wheel 29 is driven by means not shown to turn at any desired speed thereby causing the rotation of the die 15. As shown in the drawing the die 15 is rotated clockwise (as seen from below). The aluminum 19 solidifies in the die 15 to form a solid rod 31 having a helical projection 32 formed by the groove 18. The rotation of the die 15 continuously ejects the rod 31 by means of a screw action, in other words the reaction between the walls of the groove 18 and the helical projection 32. A pair of driven pinch rolls 33, 34 are mounted beneath the other elements of my apparatus to further urge and guide the cast rod.

An embodiment of my invention adapted to apply a cable sheath is shown in FIGURE 2. In this figure a cable 40 is passed continuously through a core tube 41 having a tapered bore 42. The word "cable" is used in this specification to designate any elongated member which it is desired to cover with a sheath as shown herein and includes such commonly sheathed members as single insulated conductors, and multiple-conductor cable cores.

The core tube 41 has an external helical thread 43. Spaced from the core tube 41 and concentric thereto is a die 44 with a cooling jacket 45 having cooling passageways 46 and cooling fluid ports 47, 48. Feeding into the annular space between the core tube 41 and the die 44 is a funnel-shaped chamber 49 holding a pool of molten aluminum 50 supplied through a conduit 51 connected through a pump 52 and a valve 53 to a supply

tank 54. The chamber 49 is closed by a pressure cover 55 which is connected by means of pressure tubing 56 through a valve 57 to a source of pressurized gas, not shown. The core tube 41 has an upper portion 58 that extends through the cover 55, by means of a stuffing box 59. A sprocket ring 60 is fastened to the top of the core tube extension 58 and a chain belt 61 connects the sprocket 60 to a sprocket wheel 62. The die 44 has a bottom flange 63 to which is fastened a sprocket ring 64 which is linked by means of a chain belt 65 to a sprocket wheel 66. The sprocket wheels 62 and 66 are mounted on a common drive shaft 67 driven by a means not shown. The number of teeth in the sprocket wheel 62 equals the number of teeth in the wheel 66 and the teeth in the sprocket 60 are equal in number to the teeth in the sprocket 64 so that the die 44 turns at the same r.p.m. as the core tube 41. The die 44 has an internal helical groove 68 having a contour uniformly spaced from and matching the helical configuration of the thread 43 on the core tube 41. Molten metal from the pool 50 fills the annular space between the die 44 and the core tube 41 and solidifies to form a helically grooved sheath 69 spaced from the cable 40 by the thickness of the walls of the core tube 41. The die 44, however, extends below the core tube 41 which has a bottom edge 70. This lower portion 71 of the die 44 is tapered downwardly and has a swaging action on the sheath 69 compressing it inwardly against the surface of the cable 40. Although I have shown the lower portion 71 of the die 44 integral therewith it will be understood that this swaging portion may be separated from the remainder of the die 44 and separately driven, and may be driven at a speed differing from the speed of the die 44 and the core tube 41 to allow for a greater pitch in the helix when it has been swaged down.

The alternative embodiment of my invention shown in FIGURE 3 is particularly advantageous for extruding hollow tubes. In this apparatus an internal wall 80 of a die 81 is smooth and free from any helical thread but I have provided a core 82 with an external helical thread 83. The die 81 remains stationary while the core 82 is rotated to eject a cast cylinder 84 by the interaction of the thread 83 and an internal matching groove 85 formed in the cylinder 84. Cooling of this casting is accomplished not only by a cooling jacket 86 around the die 81 and integral therewith but by internal cooling of the core 82. For this purpose the core 82 is hollowed out to form a chamber 87 into which cooling water is introduced through a pipe 88 from a source not shown, and discharged through a pipe 89. The chamber 87 is sealed by means of a plug 91 through which the pipes 88 and 89 are sealed. The plug 91 is set in a stuffing box 92 so that the pipes can remain stationary while the core 82 is rotated by means of a sprocket ring 93, chain 94 and sprocket wheel 95 driven by means not shown. To prevent the cooling water from solidifying the metal in the chamber 49 a close fitting bushing 97 is inserted at the bottom of the pipe 89 and the pipes 88, 89 are insulated by laggings 98, 99 between the plug 91 and bushing 97.

It will be understood that the embodiments of my invention shown in the drawing are not limiting and that the elements of the illustrated apparatuses may be recombined within the scope of my disclosure. For example, by inserting a central core, similar to the core 82 of FIGURE 3 but with smooth, rather than threaded,

outer walls, in the apparatus of FIGURE 1 the apparatus can be made to cast a hollow pipe instead of a solid bar. Additionally, if the thread 43 is omitted from the core tube 41 of FIGURE 2, the extruded cable sheath will have the form of a pipe with an outer thread and smooth inner surface rather than the corrugations shown.

I have invented a new and useful casting apparatus for which I desire an award of Letters Patent.

I claim:

1. Apparatus for casting a hollow cylinder comprising a cylindrical core, a die concentric to said core defining an annular space therewith, said die having an internal helical groove and said core having an external helical projection matching said internal groove, means for introducing a liquid solidifiable material into the annular space between said core and said die, means for cooling said apparatus so as to solidify said material in the form of a helically grooved cylinder having substantially uniform wall thickness, means for rotating said core and die at a common speed while restraining said cylinder against rotation so as to eject said cylinder.

2. Apparatus for continuously casting a cable sheath comprising a cylindrical core tube having a bore for receiving a cable, said core tube having an external helical projection, a die concentric to said core tube having an internal helical groove matching said projection and defining an annular space therewith, means for introducing a liquid, solidifiable material into the annular space between said core tube and said die, means for cooling said die so as to solidify said material in the form of a helically grooved sheath having substantially uniform wall thickness, means for rotating said core tube and said die at a common speed relative to said sheath so as to eject said sheath, and means for swaging said sheath onto said cable.

3. Apparatus for continuously casting an aluminum cable sheath onto an electric cable comprising a storage supply for molten aluminum, a core tube having a bore for receiving a cable, a closed chamber for molten aluminum surrounding said core tube, said core tube extending above the level of molten aluminum in said chamber, means for maintaining a gas under pressure above the aluminum in said chamber, conduit means between said chamber and said storage supply, pumping means for pumping molten aluminum through said conduit means into said chamber, a die concentric to said core tube and defining an annular space therewith, said die having a helical internal groove and said core tube having a helical external projection matching said groove, said chamber communicating with said space whereby aluminum flows into and fills said space, means for cooling said die so as to solidify said aluminum in the form of a helically grooved sheath having substantially uniform wall thickness, means for rotating said core tube and said die relative to said sheath so as to eject said sheath, and means for swaging said sheath onto said cable.
